Patented Nov. 11, 1913.

UNITED STATES PATENT OFFICE.

OLOF BOECKER, OF BERLIN-WILMERSDORF, GERMANY.

SIGHT FOR GUNS.

1,078,411.

Specification of Letters Patent. Patented Nov. 11, 1913.

Application filed May 16, 1912. Serial No. 697,616.

To all whom it may concern:

Be it known that I, OLOF BOECKER, a subject of the Grand Duke of Finland and the Emperor of Russia, residing at Berlin-Wilmersdorf, in the Kingdom of Prussia, Germany, have invented certain new and useful Improvements in Sights for Guns; and I do hereby declare the following to be a full, clear, and exact description of the invention, such as will enable others skilled in the art to which it appertains to make and use the same.

My invention relates more particularly to sights which automatically adjust themselves within a vertical plane, and the object of the improvements is to provide a sight of this class which is simple in construction and reliable in operation, so that it may be used in hand fire arms to avoid the errors in aiming the gun which are caused when aiming with the gun in inclined position.

With this object in view my invention consists in providing rocking supports for the front and rear sights of the gun on the barrel itself and connecting the sights with each other, for example by means of a rod, a tube, or the like, which if required carries a weight adapted to swing within a cavity formed in the frame of the gun.

A further object is to provide means whereby undue oscillation of the pendulum and the sights is avoided when handling the gun. For this purpose I provide the sights with locking means which are thrown into inoperative or nonlocking position when aiming the gun, for example by means of the trigger which when pulled retracts said locking means out of engagement with the sights prior to firing.

For the purpose of explaining the invention an example embodying the same is shown in the accompanying drawing, in which the same letters of reference are used in all the views to indicate corresponding parts.

In said drawings—Figures 1 and 2, are longitudinal sections of the gun taken respectively at the front and rear sights, Figs. 3 and 4, are cross-sections taken respectively along the lines A—B and C—D of Fig. 1, and Figs. 5 and 6 are detail views showing the locking device for the sight.

Referring to the example illustrated in the drawing, the front sight *h* and the rear sight *g* are respectively secured to sleeves *j*

and *i* having a rocking support on outer bushings *l* and *k* respectively secured to the barrel *o*. To reduce friction antifriction rollers *a* are preferably interposed between the bushings *l*, *k* and sleeves *j*, *i*. The said sleeves and rollers are inclosed within dust-proof casings consisting of two sections *m* and *n* which sections are respectively secured to the frame *p* and the sleeves *i* and *j* and permit oscillation of the sight about the barrel *o*. Preferably an insulation is provided between the barrel and the bushings *h* and *l* to avoid objectionable heating of the bearings of the sight.

The sleeves *i* and *j* are connected with each other by means of a rod or tube *c* which as shown in the example illustrated is equipped with a weight *r* having oscillating movement within a cavity *d* formed in the lower and rear part of the frame *p*.

The sight is adapted to be locked in position by means of a slide *f* which is guided in a sleeve *s* secured to the frame *p* and is operatively connected with a suitable part of the gun, for example with the trigger *u*. As shown the slide *f* is connected with the trigger by means of a link *t*. The front end of the slide *f* and the rear end of the rod *c* are respectively formed with an angular notch and an edge coöperating with each other to lock the sight. In the example shown the notch is formed in the slide and the edge on the rod. Normally the slide is in locking position. But when the trigger is pulled, the slide is retracted out of engagement with the rod *c* during the first part of the movement of the trigger and before firing, so that the sight is free to oscillate and to adjust itself in a vertical plane under the action of the weight *r*. The side walls of the angular notch of the slide *f* provide a guide for the rod *c* when being retracted, so that undue oscillation of the sight is avoided.

I claim herein as my invention:

1. In a small arm the combination with the barrel, the front sight, and the rear sight, of rocking supports for said sights provided on the barrel and permitting automatic adjustment of the sights within a vertical plane, and means to rigidly connect said sights with each other.

2. In a small arm, the combination with the barrel, the front sight, and the rear sight, of rocking supports for said sights provided on the barrel and permitting auto-

matic adjustment of the sights within a vertical plane, and a rod connecting said sights with each other.

3. In a small arm, the combination with the barrel, the front sight, and the rear sight, of rocking supports for said sights provided on the barrel and permitting automatic adjustment of the sights within a vertical plane, and a tubular rod connecting said sights with each other.

4. In a small arm, the combination with the barrel, the front sight, and the rear sight, of rocking supports for said sights provided on the barrel and permitting automatic adjustment of the sights within a vertical plane, and a rod located below the barrel and connecting said sights with each other.

5. In a small arm, the combination with the barrel, the front sight, and the rear sight, of rocking supports for said sights provided on the barrel and permitting automatic adjustment of the sights within a vertical plane, a rod located below the barrel and connecting the sights with each other, and a weight secured to said rod.

6. In a small arm, the combination with the barrel, the frame supporting the barrel and having a cavity, the front sight, and the rear sight, of rocking supports for said front and rear sights provided on the barrel and permitting automatic adjustment of the sights in a vertical plane, and rigid means connecting said sights and having oscillating movement within said cavity.

7. In a small arm, the combination with the barrel, the frame supporting the barrel and having a cavity, the front sight, and the rear sight, of rocking supports for said front and rear sights provided on the barrel and permitting automatic adjustment of the sights in a vertical plane, and a rod connecting said sights and having oscillating movement within said cavity.

8. In a small arm, the combination with the barrel, the frame supporting the barrel and having a cavity, the front sight, and the rear sight, of rocking supports for said front and rear sights provided on the barrel and permitting automatic adjustment of the sights in a vertical plane, a rod connecting said sights and located below the fulcrum of the sights, and a weight secured to said rod, said rod and weight having oscillating movement within said cavity.

9. In a small arm, the combination of a sight support rotatable on an axis coincident with the axis of the barrel, a sight carried by the support and movable therewith, means operable by a change in the position of the small arm for shifting the sight support, and means for locking said sight support.

10. In a small arm, the combination of a sight support rotatable on an axis coinci-

dent with the axis of the barrel, a sight carried by the support and movable therewith, means coöperating directly with said rotatable support for securing automatic adjustment of said support to bring the sight to a vertical position, and means for locking said support.

11. In a small arm, the combination with the barrel, the sight, and the firing mechanism, of a rocking support for said sight permitting automatic adjustment of the sight in a vertical plane, means to lock said sight, and an operative connection between said locking means and firing mechanism adapted to throw said locking mechanism into non-locking position upon operation of said firing mechanism.

12. In a small arm, the combination with the barrel, the sight, and the firing mechanism including a trigger, of a rocking support for said sight permitting automatic adjustment of the sight in a vertical plane, means to lock said sight, and an operative connection between said locking means and trigger adapted to throw said locking mechanism into non-locking position when pulling the trigger and prior to firing.

13. In a small arm, the combination with the barrel, the front sight, and the rear sight, of rocking supports for said sights provided on the barrel and permitting rocking movement of the sights about an axis passing through the barrel and automatic adjustment of the sights within a vertical plane, and means to rigidly connect said sights with each other.

14. In a small arm, the combination with the barrel, the front sight, and the rear sight, of rocking sleeves embracing said barrel and respectively carrying said front and rear sights, and rigid means connecting said sleeves.

15. In a small arm, the combination with the barrel, the front sight, and the rear sight, of rocking sleeves embracing said barrel and respectively carrying said front and rear sights, and a rod connecting said sleeves.

16. In a small arm, the combination with the barrel, the front sight, and the rear sight, of rocking sleeves embracing said barrel and respectively carrying said front and rear sights, and a rod located below said barrel and connecting said sleeves.

17. In a small arm, the combination with the barrel, the front sight, and the rear sight, of rocking sleeves embracing said barrel and respectively carrying said front and rear sights, antifriction rollers intermediate said sleeves and barrel, and rigid means connecting said sleeves.

18. In a small arm, the combination with the barrel, the front sight, and the rear sight, of bushings secured to the outside of the barrel, rocking sleeves embracing said

bushings and respectively carrying said front and rear sights, and rigid means connecting said sleeves.

19. In a small arm, the combination with 5 the barrel, the front sight, and the rear sight, of bushings secured to the outside of the barrel, insulating material intermediate said bushings and barrel, rocking sleeves embracing said bushings and respectively

carrying said front and rear sights, and 10 rigid means connecting said sleeves.

In testimony whereof I hereunto affix my signature in the presence of two witnesses.

OLOF BOECKER.
